PULLEY OR THE LIKE WITH MEANS FOR AP-
PLYING OR REMOVING ROPES, BELTS,
AND THE LIKE

Frank Russell, Oklahoma City, Okla.

Application October 7, 1936, Serial No. 104,516

4 Claims. (Cl. 74—242.6)

The invention relates to means for applying or removing ropes, belts or the like driving means to or from driving wheels, pulleys and the like. The invention while of general application defines 5 a special utility in the oil fields with particular reference to the application and removal of bull ropes to or from the bull wheels forming parts of the oil rigs in common use in such fields.

The application to and removal of bull ropes 10 from bull wheels in oil rigs at the present time involves considerable difficulty as well as danger of loss of lives to the operators.

According to my invention the bull wheel, pulley or the like to which the rope, belt or other 15 flexible transmitting device is to be applied or from which it is to be removed is equipped with one or more adjustable peripheral sections whereby the rope or the like is guided onto or off of the wheel as the same is revolved in the proper direction. This device is extremely simple to 20 operate and eliminates the present dangers.

The invention will be more readily understood by reference to the accompanying drawings showing 25 a specific adaptation of the invention to oil field apparatus but it is to be understood that such showing is simply for the purpose of illustration and not by way of limitation, the broad features of the invention being of general use and application and adapted for use with pumps of 30 all sorts and various forms of driving means employing ropes, belts or the like of round, flat or V shape.

In the drawings:—

Fig. 1 is a diagrammatic side view showing an 35 oil rig including a bull wheel embodying my invention.

Fig. 2 is a detailed plan view showing a peripheral section of the bull wheel moved to a position to guide the rope off the wheel in one direction.

Fig. 3 is a perspective view showing the rope 40 being guided in the opposite direction.

Fig. 4 is an end view of the adjustable section of the bull wheel.

Fig. 5 is a plan view of the adjustable section, 45 the ropes being removed for the purpose of showing details of construction.

Fig. 6 is a section on line 6—6, Fig. 4.

Referring to the drawings in detail the reference numeral 10 denotes an oil well rig of any 50 conventional type including a bull wheel 11 which is adapted to be operated by one or more ropes 12. According to my invention the bull wheel includes an adjustable rope applying or removing peripheral member 13 which forms part of the wheel 55 itself and which serves to guide the ropes onto

or off of the wheel when moved to the proper position to the right or left, while in the central position the adjustable section forms a continuation of the periphery of the wheel and allows the rope to operate in the usual manner.

Various adjusting means may be employed in connection with this device, one of which will be described in detail for the purpose of illustration by reference particularly to Figs. 2 to 6 of the drawings.

As best shown in Fig. 4, a plate 14 in the form of a chord extends part-way between two spokes of the wheel and may be welded or otherwise secured to the wheel as indicated at 15. From this plate are pivotally mounted one or more arcuate guide members 16 by means of bolts or the like 17 extending through the plate. These adjustable members 16 are so formed as to provide grooves 18 between adjacent members which grooves, when the peripheral members 16 are in working position, are in alignment with corresponding grooves 19 on the stationary portion of the bull wheel. It will be understood that the bull wheel may be provided with any desired number of such grooves and that the grooves may be of any suitable shape to receive round, flat or V shaped driving ropes, belts or other flexible members.

To permit adjustment of the arcuate groove carrying members 16, a sliding plane 20 is provided, adjustably mounted in the fixed plate 14. As shown three holes 21 are provided in the sliding plate any one of which is adapted to be engaged by a spring-pressed plunger 22 extending through the fixed plate 14.

The front ends of the arcuate members 16 are mounted to move with the sliding plate or bar 20 by means of a suitable pin and slot connection 23, 24.

In operation the sliding plate 20 may be adjusted in any one of three positions according to the hole which the spring-pressed plunger 22 engages. When in the central hole as indicated in Fig. 6 the arcuate members 16 are in such position that the grooves 18 formed between them are in alignment with the grooves on the stationary portion of the bull wheel. Assuming that the adjustable members are in this central position the bull wheel is adapted to operate in the usual manner and the bull rope or ropes 50 will be held in position by the grooves 18 and 19. To remove the bull rope from the wheel the shifting bar or plate 20 may be moved either to the right or to the left and held in such adjusted position by the spring plunger engaging with a 55

proper hole 21 in the bottom of the adjustable plate. The bull wheel being now revolved in the proper direction the rope will gradually unwind itself from the bull wheel.

5 5 Similar operation will suffice to apply the rope to the wheel, the wheel being of course rotated in the opposite direction from which it is rotated to remove the rope. It will be apparent that the entire operation will be simple, smooth and effective and will result in a marked saving of expense and time and loss of life.

10 10 The invention has been described in detail for the purpose of illustration but it will be obvious that many variations and modifications may be resorted to without departing from the spirit of the invention, as will be apparent to those skilled in the art.

15 15 I claim:—

20 20 1. In a device of the character described a grooved wheel having a peripheral grooved section adjustable for applying or removing a belt, rope or like flexible driving member.

2. In a device of the character described a grooved wheel having a peripheral grooved section adjustable for applying or removing a belt, rope or like flexible driving member, and means for selectively retaining said section in working position or in belt applying or removing position. 5

3. In a device of the character described a grooved wheel having a peripheral grooved section adjustable for applying or removing a belt, rope or like flexible driving member, and means for selectively retaining said section in working position or in belt applying or removing position, 10 said means including a retractable pin.

4. A grooved wheel, pulley or the like for use in an oil rig, said wheel having a peripheral grooved section adjustable for applying or removing a belt, rope or the like, and means for retaining said section in working position or in right or left belt applying and removing positions. 15 20

FRANK RUSSELL.
